[57] CLAIM

The ornamental design for an electric fence insulator, as shown and described.

DESCRIPTION

FIG. 1 is a front and upper left perspective view of an electric fence insulator showing our new design. The broken line showing of the mounting element is included for the purpose of illustrating environmental elements only and forms no part of the claimed design; FIG. 2 is a left side elevational view thereof, the right side elevational view thereof being a mirror image; FIG. 3 is a front elevational view thereof; FIG. 4 is a rear elevational view thereof; FIG. 5 is a top plan view thereof; and, FIG. 6 is a bottom plan view thereof.
